(57) **CLAIM**

I claim the ornamental design for a heating appliance, as shown and described.

DESCRIPTION

FIG. 1 is a top perspective view of the left side of the heating appliance of the present invention.

FIG. 2 is a bottom perspective view of the right side of the heating appliance of FIG. 1.

FIG. 3 is a front elevation view of the heating appliance of FIG. 1.

FIG. 4 is a rear elevation view of the heating appliance of FIG. 1.

FIG. 5 is a side elevation view of the left side of the heating appliance of FIG. 1.

FIG. 6 is a side elevation view of the right side of the heating appliance of FIG. 1.

FIG. 7 is a top plan view of the heating appliance of FIG. 1; and,

FIG. 8 is a bottom plan view of the heating appliance of FIG. 1.

In the drawings, the broken lines depict portions of the heating appliance that form no part of the claimed design.
